PLASTICS CONED DISK

Henry Kershaw, Belleville, N. J., assignor to Speed-Jack Company, Belleville, N. J., a partnership composed of Herman A. Fenning and Henry Kershaw

Application November 13, 1943, Serial No. 510,196

10 Claims. (Cl. 74—230.17)

My invention relates to improvements in a plastics coned disk, used in a variable speed transmission gearing.

In the variable speed transmission gearing, shown in Patent 2,253,921, granted to V. H. Van Sant, a plurality of coned disks are shown, which are shiftable axially with relation to each other to vary their effective diameters. To increase the range of adjustment, these disks are provided at their inner portions with spaced sets of teeth, the set of teeth carried by one disk passing into the spaces between the set of teeth carried by the other disk. These disks are formed of plastics such as "Bakelite." The set of spaced teeth on each disk usually constitutes about one-third or less of the area of the coned face of the disk. Due to this reduced area, these teeth wear, due to the action of the belt.

In accordance with the present invention, the set or sets of teeth of the coned disk is covered with a metal facing or covering, extending over the face of this disk, in whole or in part, and anchored to or imbedded in the material of the plastics disk, so that there can be no slippage between the disk and the facing or covering. In this manner, a hard face is provided for the teeth, which will eliminate the wearing action referred to.

The facing or covering is applied to the plastics disk while the disk is being molded and before the same sets.

In the accompanying drawings forming a part of this application and in which like numerals are employed to designate like parts throughout the same,

Figure 1 is a side elevation of a flat stamped blank from which the lining or covering is formed,

Figure 2 is an edge elevation of the same,

Figure 3 is a transverse section taken on line 3—3 of Figure 1,

Figure 4 is a side elevation of the formed lining or covering,

Figure 5 is a transverse section taken on line 5—5 of Figure 4,

Figure 6 is a similar view, showing two linings or coverings assembled in opposed relation, to be applied to a double coned disk,

Figure 7 is a perspective view of the formed lining or covering,

Figure 8 is a central transverse section through the completed coned disk with the linings or coverings applied thereto,

Figure 9 is a perspective view of same,

Figure 10 is a detailed section taken on line 10—10 of Figure 9,

Figure 11 is an enlarged section taken on line 11—11 of Figure 1,

Figure 12 is a similar view taken on line 12—12 of Figure 9, and,

Figure 13 is a transverse section through a completed disk, showing a slight modification of the invention.

10 In the drawings, wherein for the purpose of illustration is shown a preferred embodiment of my invention, the numeral 15 designates a circular flat blank, preferably formed of sheet steel, which is case hardened after the forming operation. This blank is stamped to provide a central circular opening 16 and an annular set of radial openings 17, having a set of radial openings 18 at their inner ends. The openings 18 are wider than the openings 17. The openings 17 form teeth covering radial sections 19, having inner extensions or flanges 20, extending circumferentially. These flanges 20 are foldable upon transverse lines 21. The radial sections 19 are foldable upon radial lines 22 for providing radial flanges 23, and the blank is also foldable upon circumferentially extending lines 24, to form outer circumferentially extending flanges 25. The blank is also foldable upon circumferentially extending lines 26 and upon an outer circumferential line 27. The blank also has small openings 28, stamped therein, preferably arranged in radial groups. When the disk is flat, Figure 11, the openings 28 are cylindrical, but when the disk is formed into the coned facing or covering 29, these openings 28 become tapered, decreasing in diameter inwardly, Figure 12.

To form each facing or covering 29 from the blank 15, such blank is placed in a press and the radial flanges 23 are bent inwardly and are 40 arranged generally at a right angle to the teeth covering sections 19, but are preferably slightly inclined and converged outwardly. The inner flanges 20 are bent inwardly and cover the inner ends of the flanges 23 and are disposed at an 45 inclined angle with respect to the sections 19 of about 30°. The flanges 25 are bent inwardly and are preferably arranged at substantially a right angle to the sections 19. The blank is further pressed and formed to provide an annular body portion 30, which is coned and has an outer convex face. The sections 19 constitute continuations of the annular body portion 30, while this body portion is bent inwardly upon the lines 26 and the outer ends of the lines 22, to form inwardly inclined circumferentially extending por-

tions 31, which carry the flanges 25. The blank is further bent upon the line 27 to provide an outer annular flange 32, which is inclined and preferably arranged at an angle of 30° to the body portion 30. After all of the bending or drawing operations are completed, the formed facing or covering 29 is then case hardened.

To produce a completed disk having two coned faces, two of the facings or coverings 29 are arranged in opposed relation, Figure 6, and suitably spaced in the mold. The plastics material such as "Bakelite" is introduced into the mold between the facings or coverings 29, and pressure applied to one or both of the facings or coverings to move them together and compress the plastics material. The mold is provided with suitable parts to form the teeth 33 and openings 34 and inclined walls 35 and the periphery 36. The plastics material is hardened under pressure, as is well known. The radial sections 19 cover the outer faces of the teeth 33, while the radial flanges 23 are imbedded in the sides of the teeth and are flush with the surfaces of the same. The flanges 20 are imbedded in the inner ends of the teeth 33. The flange 32 is imbedded in the annular body portion 36' of the formed plastics disk. The inclined portions 31 extend into the openings 34 and follow the inclined walls 35, and are imbedded therein and are flush with the faces of these walls. The flanges 25 are imbedded in the body portion 36', inwardly of and spaced from the high points 26, so that the shoulders produced by the same will not be engaged by the belts. The plastics material also enters the openings 28, Figure 12, and is anchored in these openings since they are tapered and increase in diameter outwardly.

It is thus seen that the annular body portion 30 covers the outer annular portion of the body portion 36', while the sections 19 cover the outer faces of the teeth 33. The disc produced has two coned faces, the belt-engaging portions of which are covered by the metal facing.

In Figure 13, the annular portion 30 is shorter radially and the annular flange 32 is imbedded in the body portion 36' short of its periphery. All other parts of the disk remain identical with those shown and described in connection with the first form of the invention.

When the disk used has only one coned face the lining or covering is applied to only one face of the disk.

The coned disk thus produced is used in the variable speed transmission gearing shown in Patent 2,253,921 and would be substituted for the disk 33 therein. Single faced coned disks having the lining or covering, would be substituted for the disks 28 and 41. While my improved disk may be used in this organization, the invention is not necessarily restricted to this use.

It is to be understood that the forms of my invention herewith shown and described are to be taken as preferred examples of the same, and that various changes in the shape, size, and arrangement of parts may be resorted to without departing from the spirit of my invention or the scope of the subjoined claims.

Having thus described my invention, I claim:

1. A disk formed of plastics material and including a body portion having a central opening and provided with a set of spaced teeth surrounding the central opening and forming openings between the teeth, the outer portion of the body portion and the teeth forming a coned face, and a coned metallic facing, said facing comprising

ing an outer portion to cover the body portion outer portion and inwardly projecting radial sections to cover the teeth, said sections being provided at their inner ends with axially extending flanges imbedded in the inner ends of the teeth, the facing outer portion being provided at its periphery with an axially extending flange imbedded in the disk body portion at its periphery.

2. A disk formed of plastics material and including a body portion having a central opening and provided with a set of spaced teeth surrounding the central opening and forming openings between the teeth, the outer portion of the body portion and the teeth forming a coned face, and a coned metallic facing, said facing comprising an outer portion to cover the body portion outer portion and inwardly projecting radial sections to cover the teeth, said sections being provided with axially extending flanges imbedded in the teeth, the facing outer portion being provided with an axially extending flange imbedded in the disk body portion.

3. A disk formed of plastics material and including a body portion having a central opening and provided with a set of spaced teeth surrounding the central opening and forming openings between the teeth, the outer portion of the body portion and the teeth forming a coned face, and a coned metallic facing, said facing comprising an outer portion to cover the body portion outer portion and inwardly projecting radial sections to cover the teeth, each section being provided with inwardly bent flanges at its longitudinal edges and which are imbedded in the edges of the tooth, each section being provided at its inner end with an axially extending flange imbedded in the tooth, the facing outer portion being provided near its periphery with an axially extending flange imbedded in the disk body portion.

4. A disk formed of plastics material and including a body portion having a central opening and provided with a set of spaced teeth which surround the central opening and forming openings between the teeth, the outer portion of the body portion and the teeth forming a coned face, and a coned metallic facing, said facing comprising an outer portion to cover the body portion outer portion and inwardly projecting radial sections to cover the teeth, said sections being provided at their longitudinal edges with axially extending flanges which are imbedded in the edges of the teeth, said sections being provided at their inner ends with axially extending inclined flanges which are imbedded in the teeth near their inner ends, the facing outer portion being provided with an axially extending inclined flange imbedded in the disk body portion.

5. A disk formed of plastics material and including a body portion provided near its inner portion with a set of spaced teeth forming openings between the teeth, said openings having inclined bottom walls, the outer portion of the body portion and the teeth forming a coned face, and a coned metallic facing, said facing comprising an outer portion to cover the body portion outer portion and inwardly projecting radial sections to cover the teeth, said sections being provided with axially extending flanges which are imbedded in the teeth, said facing outer portion being provided between the radial sections with inclined circumferential sections which are imbedded in the inclined bottom walls of said openings and having axially extending flanges imbedded in said bottom walls inwardly of the high

points of said bottom walls, the facing outer portion being provided with an axially extending flange imbedded in the disk body portion.

6. A disk formed of plastics material and including a body portion having a central opening and provided with a set of spaced teeth surrounding the central opening, the body portion and teeth forming a coned face, and a coned metallic facing having an outer portion to cover the body portion and sections to cover the teeth, said facing outer portion and sections having parts imbedded in the body portion and teeth.

7. A disk formed of plastics material and including a body portion having a central opening and a set of spaced teeth surrounding the central opening, the body portion and teeth forming a coned face, and a coned metallic facing to cover the body portion and teeth, said facing having openings for the passage of the plastics material.

8. A disk formed of plastics material and including a body portion having a set of spaced teeth, the body portion and teeth forming a coned face, a coned metallic facing to cover the body portion and teeth, said facing having openings for the passage of the plastics material, said openings being tapered and increasing in diameter outwardly.

9. A disk formed of plastics material and including a body portion having a central opening and provided near the opening and upon its opposite faces with sets of spaced teeth forming

openings between the teeth, said openings having bottom walls which are inclined downwardly toward said central opening, the outer portion of the body portion and the sets of teeth forming coned faces, and a coned metallic facing for each coned face, said facing comprising an outer portion to cover the body portion outer portion and inwardly projecting radial sections to cover the teeth, said sections having axially extending longitudinal flanges which are imbedded in the teeth and axially extending flanges at their inner ends which are imbedded in the teeth, said facing outer portion being provided between the radial sections with circumferential sections which are inclined downwardly toward the central opening are imbedded in the inclined bottom walls of said openings and having axially extending flanges at their inner ends which are imbedded in said bottom walls, the outer facing portion being provided with an axially extending flange imbedded in the disk body portion.

10. A cone disk pulley formed of plastics material and including a body portion having a central opening and spaced radial teeth surrounding the central opening, and metal strips applied to the faces of the teeth, said metal strips having openings, the plastics material being molded to the metal strips and passing into the openings, the body portion and teeth forming a coned face.

HENRY KERSHAW.
